(57) **CLAIM**

(**) Term: **14 Years**

The ornamental design for an LED lateral illuminator for
microscope, as shown and described herein.

(21) Appl. No.: **29/280,741**

DESCRIPTION

(22) Filed: **Jun. 6, 2007**

FIG. 1 is a perspective view of the LED lateral illuminator for
a microscope.

(51) **LOC (9) Cl.** 13-03

FIG. 2 is a front elevational view of the LED lateral illuminator of FIG. 1.

(52) **U.S. Cl.** D13/180

FIG. 3 is a back elevational view of the LED lateral illuminator of FIG. 1.

(58) **Field of Classification Search** D13/182;
D16/131; 359/363, 385, 387, 390; 362/217,
362/218, 259, 298, 347, 487

FIG. 4 is a left side elevational view of the LED lateral illuminator of FIG. 1; the right, opposite, side of which is a
mirror image thereof.

See application file for complete search history.

FIG. 5 is a top plan view of the LED lateral illuminator of FIG.
1; and,

(56) **References Cited**

FIG. 6 is a bottom plan view of the LED lateral illuminator of
FIG. 1.
